JOSEPH REPETTI, OF PHILADELPHIA, PENNSYLVANIA.

Letters Patent No. 96,963, dated November 16, 1869.

IMPROVEMENT IN VELOCIPEDES.

The Schedule referred to in these Letters Patent and making part of the same.

Be it known that I, JOSEPH REPETTI, of Philadelphia, in the county of Philadelphia, and State of Pennsylvania, have invented certain new and useful Improvements in Velocipedes; and I do hereby declare that the following is a full, clear, and exact description of the construction and operation of the same, reference being had to the annexed drawings, in which—

Figure 1 is a side view,

Figure 2, a plan, and

Figure 3, a section of the back axle, showing its peculiar construction.

The velocipede herein described is of the three-wheeled kind, the front wheel *a* being used as a guide-wheel, as usual.

The back axle is made so, that for the purpose of changing the direction of the motion of the machine, one of the wheels *c c* may be turned independently of the other.

The axle is not continuous from one wheel to the other, but is cut in two in the middle, each part, *b*, having independent bearings, and an independent propelling-apparatus.

The wheels are fastened upon pins, *d d*, which latter are united with the axle-sections *b b*, by means of couplings *e e*, in such a manner that they may be readily detached, so that, with the wheels *c c* removed, the apparatus may be put through a narrower space than would otherwise be possible.

In fig. 3 are shown two kinds of couplings, by which the connection may be effected, but it is not necessary to describe them more fully, as similar appliances are daily used in common "shafting."

Each part *b b* of the driving-axle is supported and turns in bearings *f f g g*; *f f* being connected with the bearing *h* of the stirrup *i*, by means of the brace-rods *j j*; and *g g*, after being united with *f f* by the ribs *g' g'*, support and connect the seat *k* and guide-lever *x*, from whence another extension runs to the boss or bearing *h*.

Another brace runs off immediately above *g' g'*, carries the pulley-support *p*, and then also joins the boss *h*.

The power is applied to the machine by means of levers *m m*, which oscillate upon the hubs of the cams *n n*, which latter carry straps *o o*.

These straps pass over pulleys *p p*, and have their ends provided with hubs *q q*, capable of sliding freely along the levers *m*, and of being fastened at any point thereon by set-screws, or otherwise, so that by moving the hubs *q q* away or toward the fulcrum of the levers *m m*, an equal motion of the latter will produce a greater or less angular movement of the cams *n n*.

This angular motion is communicated to the axles *b b* by means of helical springs *r r*, contained in the interior of *n n*, and wound loosely around *b* and *b*. One

end of these springs being fastened to the cams, it follows, that when the latter are pulled by the straps *o o* in one direction, the springs contract diametrically, grasping *b b* firmly, thereby causing the latter to revolve with the cams.

When the cams *n n* are pulled back to their original position by the springs *r' r'*, the convolutions of the springs *r r* expand, release their hold upon the axles *b b*, (allowing the latter to continue their previous forward motion,) and the levers or treadles are elevated, ready for the next stroke.

The bearing *h*, for the stirrup *i*, contains a helical spring, *s*, through which the cylindrical stem *e* of stirrup passes, one end of the spring pressing against the interior of the top of the bearing *h*, while the lower end bears against the collar *u* on the stem *t*, so that any shocks to the forward wheel, caused by inequalities of the ground, will thereby be neutralized.

The top of the stem *t* carries the wheel *v*, to which cords *v' v'* are fastened, at *w*.

These cords pass to the double lever *x*, so that by turning the latter on its fulcrum, its motion is communicated to the stem *t* and stirrup *i* by means of said cords, thereby changing the motion of the machine to a different direction.

The brake consists of a shoe, *y*, supported by a lever, *z*.

A cord, *z'*, connects with the outward arm of this lever in such a manner, that by pulling said cord, the shoe tightens upon the tire of the wheel.

It will be noticed that the cord passes through the side of the stem *t*, and out at its centre at the top, so that its motion cannot be affected by the vertical oscillating motion of the stirrup.

The operation of the machine is as follows:

The operator occupies the seat *k*, touching with his feet the treadles *m m*. By depressing the treadles alternately, or at the same time, the straps *o o* pull the cams *n n* around, and the springs *r r*, in their interior, tightening on the axle-sections *b b*, revolve them and the hind wheels *c c*, and thus carry the machine forward.

If the operator ascends a steep hill, the danger of the machine running backward and becoming unmanageable is in this contrivance entirely avoided, as, on the backward motion of the vehicle, the helical springs *r r* at once tighten on the axles *b b*, and prevent all further motion.

I do not claim, as my invention, the idea of producing an intermittent revolving motion by means of helical springs; but

What I claim, is—

1. The helical springs *r r*, in combination with the axle-sections *b b*, substantially as and for the purpose specified.

2. The combination of the helical springs $r' r$ with the cams $n' n$, substantially as and for the purpose herein set forth.

3. The combination of the helical springs $r' r$ and cams $n' n$ with the levers or treadles $m' m$, straps $o' o$, pulleys $p' p$, and support p' , together with the springs $r' r'$, substantially as and for the purpose specified.

4. The arrangement of the bearings $f' f' g' g$, for the axles $b' b$, ribs $g' g$, brace-rods $j' j$, and seat k , substantially as and for the purpose herein specified.

5. The opening for the brake-cord z' , entering the

side of the stem t , and issuing therefrom at the centre of its upper end, substantially as and for the purpose set forth in this specification.

In witness whereof, I have signed my name, in the presence of two subscribing witnesses, this day of 1869.

JOSEPH REPETTI.
